Primary Examiner — Kimberly Barnes*Assistant Examiner* — Alexandria Dubus(74) *Attorney, Agent, or Firm* — Bruce S. Shapiro(57) **CLAIM**

The ornamental design for a crate as shown and described.

DESCRIPTION

FIG. 1 is a top/right perspective view of a crate showing our new design;

FIG. 2 is a bottom/right perspective view thereof;

FIG. 3 is a front view thereof;

FIG. 4 is a rear view thereof;

FIG. 5 is a right side view thereof;

FIG. 6 is a left side view thereof;

FIG. 7 is a top thereof; and,

FIG. 8 is a bottom view thereof.

The broken lines shown in the Figures depict portions of the crate that form no part of the claimed design.

1 Claim, 8 Drawing Sheets(56)
